BY Victor J. Evans

ATTORNEY

UNITED STATES PATENT OFFICE

EGBERT HERRON THOMPSON, OF JACKSONVILLE, FLORIDA

BLOTTER

Application filed June 21, 1929. Serial No. 372,760.

This invention more particularly relates to improvements in blotters and other devices for absorbing or drying the ink from pen inscriptions.

- 5 An object of the invention contemplates the provision and arrangement of means whereby the blotters may be conveniently worn upon the palm of the hand and yet permit unrestricted use of the hand for other purposes.
- 10 A further object of the invention embodies retaining members for the blotter having detachable connection therewith to permit replacement of the blotting material when necessary or desired.
- 15 With the above and other objects in view, the invention further consists of the following novel features and details of construction, to be hereinafter more fully described, illustrated in the accompanying drawing and 20 pointed out in the appended claim.

In the drawing:—

Figure 1 is an elevation of my invention as applied upon the palm of a hand.

Figure 2 is an elevation of the back of a 25 hand illustrating by dotted lines the arrangement of the invention thereon.

Figures 3 and 4 are horizontal sectional views taken on lines 3—3 and 4—4 respectively through Figure 2 of the drawing.

30 Figure 5 is a fragmentary detail sectional view of the blotter retaining means.

Referring to the drawing in detail wherein like characters of reference denote corresponding parts, the reference character 10 indicates the base of the blotter support and which is to be constructed of some pliable material which will permit freedom in the use of the hand, and which may be in the nature of rubber, leather and the like. The 35 base disclosed in outline in Figures 1 and 2 of the drawing is shaped to cover the adjacent portions of the palm and wrist. Strap members 11 and 12, carried upon the opposite side edges of the reduced projecting portion arranged beneath the wrist of the wearer's hand are adapted for adjustable connection upon their opposite ends through the use and employment of a buckle or like fastening, such as indicated at 13.

50 In view of the fact that cupping of the

hand enlarges the joints, an adjustable strap, as mentioned in the foregoing, would not permit freedom in the use of the hand and would cause binding. To overcome this apparent difficulty, I provide a strip, indicated as at 14, of elastic characteristics and which is looped through a yoke 15 carried within the doubled end of a strap 16 secured to the upper side and adjacent an outermost edge of the base member 10 in the manner as best shown in Figure 4 of the drawing. An end 17 of the elastic strip 14 is secured to the base 10 in a manner similar to the strap 17 and is subsequently passed through a sliding adjusting buckle 18 carried upon the opposite end of the elastic strap.

The retaining members consist of plates 19 having penetrating prongs 20 formed thereon of bendable character and which are offset from the plates, projecting through and bent reversely upon the base to sustain the retaining elements at diagonally opposite corners of a square as defined upon the under surface of the base 10. The opposite ends of the plates are shaped to points and which have the loose pieces or flanges 21 of the plates formed thereby reversely disposed over and upon the plates proper to retain the adjacent portions of a square of blotting material, such as indicated at 22 thereagainst.

It is obviously apparent that the portions 21 may be sprung away or otherwise spaced temporarily from the plates 19 during the removal and replacement of blotting sheets.

It is to be noted that the present invention may be used to advantage by clerks, book-keepers, auditors, accountants, students, and in fact everyone who uses a pen constantly.

The invention is susceptible of various changes in its form, proportions and minor details of construction, and the right is herein reserved to make such changes as properly fall within the scope of the appended claim.

Having thus described the invention, what is claimed is:—

A blotting device comprising a base of pliable material designed for flush engagement with the palm and wrist of a hand, attaching means for the base adjustably and detachably securing the latter in position for

use, an absorbent element facing the under surface of the base, retaining members having prongs penetrating the base for disposition adjacent to and beneath the corners of 5 the absorbent element, and flanges carried upon the plates extended over and sprung against the corner portions of the absorbent element to retain the latter against displacement upon the base.

10 In testimony whereof I affix my signature.
EGBERT HERRON THOMPSON.
